UNITED STATES PATENT OFFICE.

FRANCIS BRUCKER, OF SHELBY, OHIO, ASSIGNOR TO THE STANDARD MANUFACTURING CO., A CORPORATION OF OHIO.

COMBINED DOOR CLOSER AND CHECK FOR DOORS.

1,007,523.

Specification of Letters Patent. Patented Oct. 31, 1911.

Application filed January 30, 1911. Serial No. 605,599.

To all whom it may concern:

Be it known that I, FRANCIS BRUCKER, citizen of the United States, residing at Shelby, Ohio, have invented certain new and useful Improvements in Combined 5 Door Closers and Checks for Doors, of which the following is a specification.

My present invention relates to double acting spring hinges for doors of that class in which a post or stem acts, as the door is turned or swung, upon a plunger and against a spring, the reaction of which tends to return the door to its normal or closed position.

Among the objects of the invention are to improve the construction of the hinge with a view to increased simplicity, and economy of manufacture, and efficiency and durability in use.

I have also aimed to provide in connection with spring hinge mechanism carried by the door at its lower corner, a check mechanism located beneath the floor, and to provide a check mechanism so located, of improved construction.

The invention includes the novel features of construction and combination and arrangement of parts hereinafter described and particularly pointed out in the appended claims.

The invention is illustrated by the aid of the accompanying drawings in which:

Figure 1 is a vertical sectional elevation of the hinge and check showing the lower corner of a door and a portion of the floor. Fig. 2 is a section on line 2-2 of Fig. 1, and Fig. 3 is a section on line 3-3 of Fig. 1.

Referring by reference characters to this drawing, 4 designates a frame member comprising a steel or other suitable metal strip which has one bent end 4^a secured to the edge of the door by screws as shown, and at the other end one angularly bent portion 4^b serving as an abutment for the spring, the strip being continued from the end of this bent portion in a plane parallel with the main portion or body of the strip and being secured to the lower edge of the door by means of screws.

The door is supported by and pivots upon a rotary post 5, the upper end of which is riveted or otherwise non-rotatably secured to the member 4 as indicated at 5^a, the lower portion of the post being journaled in the floor plate 6. The floor plate has an up-

wardly extending bearing 6^a provided with lateral wings or enlargements 6^b which carry pins or projections 7 which abut against the transverse shoulder 8 of the plunger 8^a. The plunger has a shank 8^b which is encircled by a spring 9, one end of which bears against an annular shoulder 8^c on the plunger while the other end bears against a nut 10 threaded on a screw bolt 11 carried by the portion 4^b of the frame member. By means of this nut the tension on the spring may be varied to suit requirements. The plunger has a forked head as shown, the arms 8^d lying upon opposite sides and embracing the post which is preferably rabbeted or reduced at this point. The head of the plunger is preferably of circular form, and a washer 12 is interposed between the head of the plunger and the frame plate. By this arrangement of the forked head of the plunger embracing the post it will be seen that the plunger is guided in its reciprocating movement on a line radial to the hinge post and coincident with the plane of the door.

In order to check the closing action of the door I provide fluid checking means which are located wholly within the floor and beneath the floor plate. For this purpose I provide beneath the floor plate an oil or other fluid containing casing 12' of which the floor plate forms a cover, and to which it is suitably secured as by means of set screws. Within the casing is located a cylinder 13 having perforated ears 13^a which enable the cylinder to be secured to the under side of the cover or floor plate by means of screws 13^b engaging threaded openings in the bosses or projections 6^c. A crank arm 14^a is provided on a sleeve 14 which is pinned or otherwise secured to the post, and this crank is connected by a link or pitman 15 with a piston 16 working within the cylinder, so that as the post turns the pitman will be reciprocated. The piston is provided with check valve controlled port 16^a (preferably ball valves) so that as the piston moves outwardly toward the open end of the cylinder, it will permit the free passage of oil from the chamber into the cylinder in rear of the piston. On the return movement of the piston effected by the closing of the door under the action of the spring, the action is retarded by the slow escape of oil from the cylinder through 110

the passages or ports 13^c and 13^d, which escape can be regulated by the screw valve 17 which extends up through the floor plate and is provided with a notched upper end 5 for convenient operation by a screw driver. The post is preferably rounded at its lower end as indicated at 5^b, so as to turn freely and without friction on a bearing projection on the bottom of the casing.

10. In order to prevent oil from creeping up about the post 5 above the floor plate, suitable packing is provided around the post, between it and the bearing 6^a, and below the level of the floor plate an air space or chamber 19 is located which receives the oil which may pass up the post to this point, and this oil is drained back into the liquid holding casing through the port 18.

It will be observed that by making the 20 bearing 6^a with its contact members fixed, and making the post 5 movable with the door, being secured thereto at its upper end and having a bearing in the oil casing at its lower end, the post constitutes a hinge pin 25 for the door which is strongly supported and sustained, and in this respect secures an important advantage over the construction shown in my Patent 918,502, where there is no central movable post and where the rigid 30 post is supported only at the lower end, being unsupported at its upper end, except through the medium of a roller bearing connection.

I secure a very decided advantage in connecting the spring to the door and locating the check beneath the floor with a connecting element between, as the post 5, constitutes a hinge pin. So far as known, I am the first to provide such a construction, and 40 it has been done for the purpose of simplifying the hinge and reducing the cost. By separating the spring and checking mechanism, I am enabled to use springs of any length in the bottom of the door, and to 45 avoid the necessity for the use of a large recess in the floor, and a corresponding large casting sufficient to hold both checking and spring mechanism. As the casting beneath the floor in my construction holds the check-

ing mechanism only, it may be made of 50 minimum size and use a minimum amount of oil. It frequently happens that there is a limited space to be utilized beneath the floor, and a casting of the size required in my construction can be readily used in the most 55 limited space where a larger casting could not be so used.

Having thus described my invention what I claim is:

1. In combination with a door hinge 60 frame, a hinge post supporting the door hinge frame, a floor member supporting the hinge post, said hinge post being rotatable in relation to one of said elements and fixed in relation to the other, stationary contact 65 members located on diametrically opposite sides of the post, a plunger having a face adapted to bear against the contact members, and means carried by the plunger head embracing the hinge post and constituting 70 the sole guiding means for the plunger, and a spring under tension for operating the plunger.

2. A spring hinge comprising a hinge frame, a hinge post secured thereto at its 75 upper end, a bearing in which said post is journaled, stationary contact members on each side of the hinge post, a plunger supported on the bearing and having a transverse face adapted to bear against the contact members, and arms embracing opposite sides of the post and having guiding contact therewith to prevent lateral movement of the plunger, substantially as described.

3. A combined spring door hinge and 80 check, comprising spring mechanism carried by the door for effecting the closing thereof, checking mechanism located beneath the floor and a connecting device between the spring mechanism and the checking mechanism.

In testimony whereof, I affix my signature in presence of two witnesses.

FRANCIS BRUCKER.
